UNITED STATES PATENT OFFICE

19,730

CHUCKING DEVICE

William F. Groene, Cincinnati, Ohio, assignor to
The R. K. Le Blond Machine Tool Company,
Cincinnati, Ohio, a corporation of Delaware

Original No. 1,878,130, dated September 20, 1932,
Serial No. 297,881, August 6, 1928. Application
for reissue September 18, 1934, Serial No.
744,565

22 Claims. (Cl. 82—40)

My invention relates to the manufacture of crank shafts, and more especially to the accurate turning, in a rapid and economical manner, the cylindrical bearing portions of such shafts, as for example the pin bearings thereof.

The general object of my invention is to increase the accuracy of finish in such turning; objects subsidiary thereto being especially firm holding of the work piece in chucking apparatus, accurate location and maintenance of location of the work piece in the chucking apparatus, freedom from torsional distortion or twisting of the piece in chucking, and rapid production while meeting all of these requirements.

In applying power operated chucking jaws at both ends or at an unclamped end of a crank shaft in a lathe, a very critical situation arises when the portions of the crank shaft engaged by the jaws are out of accurate radial angle to the axis of the shaft. The result is to twist the shaft, and to hold it in twisted position during the lathe operations, so that the turning of the pins of the shaft will not be accurate, when the shaft springs back upon being released.

Among other things, my present invention contemplates the machining at both ends of the shaft of locating faces or spots, and the chucks themselves are equipped with a locating element which cooperates with a moving wedge to engage the locating faces usually on both terminal webs of the crank shaft. Also the web engaging jaws of the chucks are formed by circular walled chambers in the chuck body, forming a bearing for the jaws which are mounted therein. This provides a very strong and safe acting mechanism. Also the wedging rods which operate the jaws have specially shaped faces so as to enable the wedges to move the jaws into position by a short movement and then tighten the jaws by a continued movement at a lesser wedging angle.

I accomplish my objects by those methods, and by those provisions, both as to the work piece and the novel chucking apparatus, as will hereinafter be more specifically pointed out and claimed.

In the drawings:

Figure 1 is a front elevation of a chucking device embodying my invention.

Figure 2 is a vertical longitudinal section on the line 2—2 of Fig. 1.

Figure 2a illustrates the left end of the cylinder omitted from Fig. 2 for lack of space.

Figure 3 is a horizontal longitudinal section on the line 3—3 of Fig. 1.

Figure 4 is a vertical section on the line 4—4 of Fig. 2.

Figure 5 is a detail side elevation of one of the jaw operating rods.

Figure 5a is a detail front elevation of one of the chuck jaws.

Figure 6 is a side elevation of a crank shaft work piece in an incompletely shown stage according to my improved method.

Figure 6a is an enlargement of a left end part 10 of the work piece as shown in Fig. 6, including the representation of a part of abutment means locating the piece according to my invention.

Figure 7 is a vertical cross section on the line 7—7 of Fig. 6a, the abutment means at opposite 15 sides being indicated, in their relation to the work piece, in broken lines.

Figure 8 is a similar view illustrating a modification of the work piece, and by broken lines indicating, in their relation to this modified work 20 piece, the abutment means at opposite sides.

I have illustrated no parts of the lathe, but one of the chucks. It will be understood that like chucks may be used at both head and tail stock of the lathe.

The chuck body 1 is shown separately from its mounting and operating parts, but it will be understood that the body will be journaled at 2, and equipped with a driving gear at 3. The power means for the chuck comprises an air cylinder 4 with its piston 5, and a coaxial air cylinder 6 of smaller bore, with its piston 7. The piston rod 8 of the piston 5, extends through the piston 7, and is provided with an extension 9. The piston 7 has a tubular extension 10 which carries a 35 gland for packing the rod 8, and a tubular piston rod 11, secured to the extension 10, surrounds the portion 9 of the inner piston rod. The portion 11 has a sleeve 12 fast thereon, which is keyed at 13 to slide in the chuck body without rotation therein.

The chuck is illustrated as in engagement with a crank shaft A (Figs. 6 and 7) having the flange end 14, a line bearing 15, and a cheek or web 16. In preparing the shaft for turning, it is placed in a 45 milling machine, and locating faces B, B are cut in the web 16, and also in exact alignment therewith locating faces C, C are cut in the web 16 at the other end of the shaft. Instead of cutting away part of the webs, they may be made 50 with lugs D, D thereon, as shown for the web 16a in Figure 8, and then the outer faces of the lugs are milled in perfect alignment end for end of the shaft.

In the outer end portion 1a of the chuck body 55

which is U-shaped to permit the shaft to be dropped therein, is a hardened centering and bearing plate 17 on which the end line bearing of the crank shaft rests. Located on a ledge 18 on the body portion 1a, is a hardened abutment or locating block 18 which engages one of the locating faces on the web of the shaft. To cooperate with this fixed abutment which is arranged for the particular shaft to be employed, I provide a clamping and positioning arm 19, which is pivoted on a pin 20 in the chuck body, and pressed by a spring 21 away from engaging position. This arm has a wedge face 22, on the side of its free end part facing from the work, and its position is such that its face toward the work engages the other locating face on the shaft web.

To operate the arm 19 I employ the outer piston rod 11, and provide a sliding bar 23, which bar moves in a groove in the chuck head and has a wedge face to coact with the face 22 on the arm 19.

The bar 23 has a slot 25 therein, through which a lever 26 passes, said lever having its outer end pivoted at 27, and having an enlarged rounded middle portion 28 which engages the walls of the slot. The lever 26 has a rounded knob 29 at its inner end.

In a channel in the sleeve 12 on the outer piston rod 11, a bar 30 is mounted and pinned as at 31. The bar has a bifurcated end 32, the opening 33 of which engages over the knob 29.

When, then, the piston 7 is moved to right or left, the tubular rod 11, through the medium of the sleeve thereon, reciprocates the bar 30. The bar rocks the lever 26, which moves the bar 23, said bar actuating the locating arm by a wedging action. It should be noted further that the piston 7 and its cylinder are of smaller bore than the other piston and cylinder, so that they operate ahead of the chucking jaw operating parts.

The chucking jaw elements of my device consist of a pair of heavy partial discs 34, which rest in semi-circular recesses 35 in the chuck head 1a. The jaws are pivoted at 36, and their peripheries are curved on the pivots as a center, and engage as a bearing in the recesses 35. Springs 37 mounted in the chuck head and secured to the discs 34, tend to hold the discs in non-engaging position with the work. Non-engaging position is indicated at dotted lines 38 (Fig. 1).

A pair of sliding pins 39 are mounted in the chuck head and body and have ends which are specially faced to engage the wedge faces 41 on the back ends of the jaw discs. There are on each pin a slanting face 40 and a succeeding more slanting face 40a, succeeded by additional bevels 42 at considerably less angles than the bevels 40, 40a, so that when the pins are advanced they first quickly wedge the jaws against the work and then the faces 42 come into engagement to provide the final tight contact. The wedge faces or bevels are curved so as to compensate for the arcuated movement of the jaws.

As will be noted, the pins 39 are advanced by a mechanism which has an equalizing action, and while the sharper wedging angles are in play this equalizing action takes place. The lesser angled faces 42 are such, however, that a great pressure on the work itself will not result in wedging the pins away, whereas with the sharper angles, this might be possible due to the equalizer system, which is free to respond to differential pressure.

An equalizer yoke 43 is used to operate the jaw wedging pins, and is provided with circular knobs at its ends to engage the notches 44 in the pins. To mount the equalizer yoke and operate it, the outer end of the inner piston rod 9 is provided with a shoe 45; the rod and the shoe both being slotted as at 46. The yoke has a projection or lug 47 therein which extends into the slot and a pivot pin 48 holds the shoe and the yoke in pivotal relation to the end of the rod. The yoke is thus free to pivot on the piston rod and within the notches of the wedging pins, whereby its equalizing function is accomplished. The yoke is formed with a hole 49 at its central portion, said hole being larger at its outer ends, and extending through the lug, where it is tapped to receive a bolt 50. The pivot pin has a hole in it which is engaged by the tip 50a of this bolt, thus holding the pivot pin in position. A locating piece 51 in the form of a cup lies over the end of the bolt in the enlarged outer end of the hole 49, and is engaged by a spring 52, which projects it forward.

As stated, I have not illustrated an entire lathe. It will be understood that a device such as described may be used at both ends of the shaft and both operated simultaneously, which can be done without danger of twisting the shaft. The two chucks will, as is usual, have a common driver so that their relative positions remain uniform at all times.

To operate the chucks air or other fluid under pressure is admitted to and exhausted from the two piston cylinders for each chuck through ports 53 and 54, in an axial shaft, which cooperates with the usual manifold sleeve. The two cylinders are in one casting with common posts. I have shown a needle valve at 55 to vary the action of the inner cylinder, the piston of which is to advance more rapidly than the other piston, as has been noted.

The air admitted through the port shaft and its manifold supplies the pressure whereby the two pistons of the chucks are advanced or retracted serving to locate and clamp a crank shaft in place. The locating devices engage the ends of the crank shaft ahead of the jaws and continue to hold them while the jaws are being applied. The jaws being applied by an equalizer will adjust themselves.

A crank shaft is set into the chucks with its webs rotated so that the locating faces rest against the locating abutments 18, and air applied to the cylinders with the result of locating the shaft under pressure, while the main jaws are rocked or rotated into engagement. Inequalities in the crank shaft web will be allowed for by the equalizer bar.

I have designed the chuck now fully described for use with crank shaft lathes which are arranged to turn all of the pins of the shafts at once and find that it is very positive and accurate in its action. The fluid pressure may be turned on and off throughout the operation, and if it is turned off after the wedges have been fully advanced, the grip of the jaws will not give way.

The method of forming locating faces on the webs of a shaft which is to be clamped in place by power, using clamping means for engaging the locating faces, is subject to considerable variation. It has solved a problem in connection with high capacity production of crank shafts and has enabled me to make possible the very rapid mounting of the crank shafts with an

accuracy which has been entirely prearranged and with no adjustments whatever.

By limiting the extent of the finished areas or locating spots on the sides of the webs, for abutment with correspondingly limited areas of abutment means of the chuck, it is possible to attain a maximum accuracy of relation of these parts to each other, and to the proper axis of each cylindrical part of the work piece, and to the abutment areas of the chuck. These are the location means transverse to the web, or, as termed, the indexing means. Having the abutment for location in the general direction of length of the web, as for example at centering plate 17, intermediate of the diametral ends of the web, also affords better accuracy than contact with a more outlying portion of the shaft. This, and the limitation of area of locating spots, makes the work independent of any shape that the webs may have.

I am thus able to chuck the pieces more rapidly in accordance with the demands of large scale production; yet without exceeding the limits of close finish on the portions to be turned; and without torsional distortion and the inaccuracies resulting therefrom as before mentioned; and with a maximum of security of holding and maintenance of location of the work piece in the chucking device, owing to the limited areas of the mutually engaging spots and abutments. The aggregate result, due to the nature of the novel partially finished forging when chucked, and due to the improved method of chucking permitted by the apparatus, is a more accurately finished, and faster and more economically produced crank shaft.

Having thus described my invention, what I claim as new and desire to secure by Letters Patent is:

40. 1. In a chucking device for crank shafts, fluid power actuating means, a wedging element operated thereby, a fixed locating abutment for engaging a web of such shaft, and movable means actuated by the wedging element and serving to force said web against the abutment, and thereby to clamp said web from opposite sides thereof.

50. 2. In a chucking device, the combination of power actuated chucking jaws to engage a web of a crank shaft, of means for locating the web of said shaft comprising a rest for a journal or pin of the shaft, an abutment to engage the web of the shaft adjacent said journal or pin, and a clamping member positioned to engage said web opposite to the abutment, and power means for actuating said clamping member.

55. 3. In a chucking device, the combination of power actuated chucking jaws to engage a web of a crank shaft, of means for locating the web of said shaft comprising a rest for a journal or pin of the shaft, an abutment to engage the web of the shaft adjacent said journal or pin, and a clamping member positioned to engage said web opposite to the abutment, and power means for actuating said clamping member, said power actuating means timed to operate in timed relation with the power actuated jaws.

70. 4. In a chucking device, the combination of power actuated chucking jaws to engage a web of a crank shaft, of means for locating the web of said shaft comprising a rest for a journal or pin of the shaft, an abutment to engage the web of the shaft adjacent said journal or pin, and a clamping member positioned to engage said web opposite to the abutment, and power means for actuating said clamping member, said power ac-

tuating means being separate from the operator of the jaws.

5. In a chucking device, the combination of power actuated chucking jaws to engage a web of a crank shaft, of means for locating the web of said shaft comprising a rest for a journal or pin of the shaft, an abutment to engage the web of the shaft adjacent said journal or pin, and a clamping member positioned to engage said web opposite to the abutment, and power means for actuating said clamping member, said power actuating means comprising a pressure driven piston and rod, a pivoted member rocked thereby, and a wedging bar moved by the pivoted member and engaging the clamping member. 15

6. In a chucking device, a chuck head, circular recesses therein at opposite sides of an opening to receive the work, jaws pivotally mounted and having circular edges which engage the recesses as a journal, and means for positively moving 20 said jaws on their pivots.

7. In a chucking device, a chuck head, circular recesses therein at opposite sides of an opening to receive the work, jaws pivotally mounted and having circular edges which engage the recesses 25 as a journal, and means for positively moving said jaws on their pivots, said means comprising wedge members slidably engaging the jaws, and power means for operating the wedge members.

8. In a chucking device, a chuck head, circular 30 recesses therein at opposite sides of an opening to receive the work, jaws pivotally mounted and having circular edges which engage the recesses as a journal, and means for pivotally moving said jaws, said means comprising wedge members 35 slidably engaging the jaws, and power means for operating the wedge members including an equalizer bar.

9. In a chucking device, the combination of 40 jaws movable into and out of position to engage the work, of power means including an equalizer element, wedging pins to actuate the jaws, said pins driven by the equalizer element, the wedge faces of the pins having a primary sharp incline and a terminating or final incline at a lesser angle. 45

10. In a chucking device, the combination of a frame, of pivoted jaws in said frame for engaging the work, power means including an equalizer element, wedging pins to actuate the jaws, said 50 pins driven by the equalizer element, the wedge faces of the pins formed on an arc and having a primary sharp incline and a terminating or final incline at a lesser angle.

11. In a chucking device, a chuck head, circular 55 recesses therein at opposite sides of the opening to receive the work, jaws pivotally mounted and having circular edges which engage the recesses as a journal, and means within the chuck acting directly on the jaws, positively moving 60 said jaws on their pivots.

12. In a chucking device for crank shafts, locating abutments, one fixed and another movable to and from the one, a wedge having an operative 65 movement for moving said other abutment toward the one abutment, and means for applying fluid under pressure to cause said operative movement of said wedge.

13. In a chucking device for crank shafts, sets 70 of locating abutments, one fixed and another movable to and from the one, in each set, wedges having operative movements for moving said other abutment toward the one abutment in the respective sets, and means for applying fluid un- 75

der pressure to cause said operative movements of said wedges.

14. In a chucking device for crank shafts, sets of locating abutments, one fixed and another movable to and from the one, in each set, wedges having operative movements for moving said other abutment toward the one abutment in the respective sets, and means for applying fluid under pressure to cause said operative movement of each wedge, whereby one movable abutment is moved in advance of another.

15. In a chucking device, the combination of a power actuated chucking jaw to engage a portion of a crank shaft near one diametral end of a web thereof, of means for locating the shaft in the device for turning a cylindrical portion thereof, comprising a rest engaging a predetermined area of said shaft between said jaw-engaged portion and the center of the cylindrical portion that is to be turned, abutment means to engage a predetermined minor side area of the web near the opposite end of the web, and a member positioned to engage a predetermined minor opposite side area of said web near its opposite end, the engagement with said minor side areas of the web being effected independently of the power actuation of the chucking jaws, and irrespective of the shape of the major portion of the web.

16. In a chucking device to hold a crank shaft for turning a cylindrical portion of the shaft adjacent to a web of the shaft, a chuck body, abutment means on said body to engage a finished area of the shaft which lies intermediate of the diametral end limits of the web, to properly locate the cylindrical portion in the device along the length of the web, spaced abutment means on said body, of limited extent to engage only minor finished areas of opposite sides of the web, to properly locate said cylindrical portion in the device along a line transverse to the web, irrespective of the shape of the major portion of the web, and means to hold the device and the shaft together with said shaft areas and abutment means in effective location-maintaining contact.

17. In a chucking device to hold a crank shaft for turning a cylindrical portion of the shaft adjacent to a web of the shaft, a chuck body, abutment means on said body to engage a finished area of the shaft which lies intermediate of the diametral end limits of the web, to properly locate the cylindrical portion in the device along the length of the web, spaced abutments on said body, each with a side of limited extent to engage only minor finished areas of opposite sides of the web to properly locate said cylindrical portion in the device along a line transverse to the web, irrespective of the shape of the major portion of the web, said device comprising abutment supporting portions within the chuck body, engaging the opposite sides of the respective abutments, directly resisting displacement of the several abutments in abutting direction and also in direction at a material angle to said abutting direction.

18. In a chucking device for holding a crank shaft by engagement with web portions thereof spaced longitudinally thereof, to hold the shaft substantially free from torsional distortion, for turning cylindrical portions of the shaft, chuck bodies mounted and connected for synchronous rotation, each having abutment means thereon to engage respective finished areas of the shaft which lie intermediate the diametral end limits of the shaft webs, to properly locate the cylindrical portions in the device along the lengths of

the webs, spaced abutment means on each body, of limited extent to engage only minor finished areas of opposite sides of respective webs, to properly locate the cylindrical portions in the device along lines transverse to the respective webs, irrespective of the shape of the major portions of the webs, and means associated with the respective chuck bodies to hold the bodies and the shaft together with said shaft areas and abutment means in effective location-maintaining contact.

19. The method of chucking a crank shaft for machining a cylindrical portion and adjacent face of a web of the shaft, which comprises finishing an area of the shaft which lies intermediate the diametral end limits of the web, to present a locating face in the direction of the length of the web, in a definite relation to a proper axis of said cylindrical portion, finishing areas of opposite sides of the web which are limited in extent to minor portions of the sides of the web, to present locating faces oppositely outward transversely of the web in a definite relation to said proper axis, irrespective of the shape of the major portion of the web, and supporting the thus partially finished shaft in a suitable chucking device by definitely located abutment means of the device presenting abutment areas to the respective finished areas of the shaft, which abutment areas correspond in disposition and limited extent to the dispositions and extent of the respective finished areas of the shaft.

20. The method of chucking a crank shaft for machining cylindrical portions and adjacent faces of webs of the shaft, by engagement with angularly aligned webs of the shaft spaced longitudinally thereof, which comprises finishing areas of the shaft which lie intermediate of the diametral end limits of the webs, to present locating faces in the general direction of the lengths of the webs, in a definite relation to a proper axis of each cylindrical portion, finishing minor areas of the opposite sides of the respective webs in a definite relation to each other and to said proper axis of each cylindrical portion, irrespective of the shapes of the major portions of the webs, and supporting the thus partially finished shaft in suitable synchronously rotatable chuck bodies by definitely located abutment means of the bodies presenting areas to the respective finished areas of the shaft, which abutment areas correspond in disposition and limited extent to the dispositions and extent of the respective finished areas of the shaft.

21. As a novel article in an incomplete stage of a novel method of manufacture of the completed article, a work piece for forming a crank shaft, comprising a cylindrical portion and a web with a face adjacent to the cylindrical portion, said work piece being prepared for chucking to turn the cylindrical portion and face, in that it is provided with a finished area lying intermediate the diametral end limits of the web in a definite relation to a proper axis of said cylindrical portion, along the length of the web, and with finished areas on opposite sides of the web which are limited in extent to minor portions of said sides of the web, in a definite relation to the proper axis of said cylindrical portion along a line transverse to the web, the limited extent of said areas permitting proper centering of the work piece for machining the cylindrical portion and face, by engagement with suitably arranged abutment means on a chucking device, and irrespective of the shape of the major portions of the web.

22. As a novel article in an incomplete stage

of a novel method of manufacture of the completed article, a work piece for forming a crank shaft, comprising cylindrical portions and webs with faces adjacent the respective cylindrical portions, said piece being prepared for chucking to machine the cylindrical portions and faces, in that it is provided with finished areas near respective spaced angularly aligned webs, lying intermediate of the diametral end limits of the webs in a definite relation to a proper axis of each cylindrical portion along the lengths of said webs, and with finished areas on opposite sides of each of said webs which are limited in extent to minor portions of said sides of said webs, in a definite

relation to each other and to the proper axis of each cylindrical portion along lines transverse to said webs, the limited extent of said areas permitting the accurate relation of those of said areas that are on webs spaced longitudinally of the work piece, for mounting the work piece, substantially free of torsional distortion and properly centered for machining the cylindrical portions and faces, by engagement with suitably arranged abutment means on respective synchronously rotatable chucking device, and irrespective of the shapes of the major portions of the webs. 5 10

WILLIAM F. GROENE.
